UNITED STATES PATENT OFFICE.

HENRY DE CORTE, OF FAIRGROVE, MICHIGAN.

TORPEDO-GUARD.

1,243,144.

Specification of Letters Patent. Patented Oct. 16, 1917.

Application filed January 26, 1917. Serial No. 144,711.

To all whom it may concern:

Be it known that I, HENRY DE CORTE, a citizen of the United States, residing at Fairgrov^e, in the county of Tuscola and State of Michigan, have invented certain new and useful Improvements in Torpedo-Guards, of which the following is a specification.

My invention relates to improvements in 10 torpedo guards, and it consists in the constructions and arrangements herein described and claimed.

An object of my invention is to provide a 15 torpedo guard of the extensible netting type, adaptable more particularly to vessels, and is arranged to be supported in such a manner on the side of a vessel, so that the netting or guard may be extended for defense or retracted at will.

20 Other objects and advantages of the invention lie in certain specific constructions as will appear from the following specification, reference being had to the accompanying drawings, in which:

25 Figure 1 is an elevation showing a portion of a vessel and illustrating the application of the guard, the guard being in an extended position for defense.

Fig. 2 is a side elevation of a portion of a 30 vessel illustrating the application of the device, and

Fig. 3 is a detail cross section on the line 3—3 of Fig. 1.

In carrying out my invention I provide 35 supporting plates 1 and 2 which may be secured to the side of the vessel in any approved manner as for instance by the rivets 3. The plates 1 and 2 are provided with bifurcated bearings 4, which merge at the 40 bottom in saddles 5. It should be observed that the saddles 5 are located somewhat below the hinge pin of the supporting plate 1, the purpose of this arrangement being presently explained.

45 A pivot pin or bolt 6 which passes through each of the bifurcated bearings 4, supports in each instance an extensible radius arm 7. The arms 7 are formed with bearings at their outer ends in which a link bar 8 is pivotally supported. The link bar 8 of each pair of radius arms 7 is fulcrumed in the bearing at the outer end of each arm 7, on a pin 9. The arrangement as described so far and as illustrated in Fig. 1, is that of an 50 articulated frame, which consists of the series of pairs of arms 7 shown more clearly in

Fig. 2, the outer ends of which are joined by the link bars 8.

When the articulated frame as described above is extended, the portions of the arms 7 adjacent the fulcrum pin 6 in the bracket plates 1 and 2, rests in the saddles 5 and are supported from further downward movement.

The link bars 8 form the supporting and 65 clamping elements for a stout metallic netting 10. The netting 10 is applied to the outer surfaces of the bars 8 and stretched tightly thereover. The netting 10 is then clamped into position by clamp plates 11 70 which are suitably apertured at intervals to permit the passage of clamping bolts 12. The clamping bolts 12 pass through the clamp plates 11 and the associated link bars 8 and grip the protective netting 75 tightly in position.

In order to insure the holding of the netting 10 in position, the bars 8 are formed with outwardly converging surfaces which terminate in a central rib 13. The clamp 80 plates 11 are correspondingly formed as will readily be observed from Fig. 3, so that when the netting is applied to the link bars 8, and the clamp plates 11 are placed thereover, the bolts 12 upon being applied will 85 draw the clamp plate 11 tightly over the rib 13 and secure a strong grip on the netting 10.

In order to raise the netting from its lowered position, I provide a plurality of bail members 12. Rope or cables 13 are joined 90 with the bail members 12 and may be wound over a suitable hoisting drum which upon rotation elevates the netting. Suitable catches may also be applied to the side of the vessel so as to support the netting in its 95 retracted elevated position adjacent the side thereof.

In operation, when it is desired to protect a vessel against submarine torpedo attacks, the guard is released from its retracted position and allowed to move downwardly into the water. The articulated arrangement of the frame, i. e. the arms 7 and the link bars 8, serves to hold the netting 10 always in a vertical position. This means that the netting 100 will lie flatly against the side of the vessel when it is retracted and will stand vertically in the water when it is extended. A torpedo in being directed toward the vessel will be 105 intercepted by the netting 10 where if it explodes no harm will be done to the vessel. It has been explained that the saddles 5

are located somewhat below the hinge pins 6 of the plates 1. By reference to Fig. 1 of the drawing, the purpose of this arrangement will be obvious. It may readily be understood that were the shield 11 supported on radius arms 7 extending at right angles to the vessel, the force of the impact of the torpedo or projectile would result in forcing the shield upwardly and it is even conceivable that a projectile or torpedo may thus be deflected under the vessel where it might explode and thus defeat the purpose of the invention. It will therefore readily be understood that a projectile striking the shield with the radius arms 7 and 8 in the position shown, the effect will be to jam the radius arms 7 tightly into the saddles 5 and obviate any tendency toward the upward movement of the shield.

20 While the construction of the device as illustrated is that of a preferred form and illustrates chiefly the prime features of the invention, obviously various modifications in the construction may be made without departing from the spirit of the invention or the scope of the claims.

25

I claim:

1. In a device of the character described, the combination with the side of a vessel, of 30 bearing plates secured thereto, each plate having a bearing portion and a saddle adj-

cent thereto, radius arms pivoted in the bearings and adapted to rest in the saddles at an inclination to the vessel, a link bar joining the outer ends of the radius arms, a netting applied to the link bars, and clamp bars for holding the netting in position the inclined position of the radius arms effecting jamming thereof into the saddles when the netting is struck by a projectile.

2. In a device of the character described, the combination with the side of a vessel, of plates secured to the vessel each having a bearing and a saddle adjacent thereto, radius arms pivoted in each bearing and adapted to rest in a saddle, a link bar joining each pair of radius arms so that the link bars may remain in a vertical position upon arcuate movement of the radius arms, said link bars being formed with a central rib, netting applied to the link bars, clamp plates having correspondingly shaped surfaces to fit over the link bar ribs, and clamp bolts for securing the clamp plates, the netting and the link bars together.

In testimony whereof I affix my signature in presence of two witnesses:

HENRY DE CORTE.
